UNITED STATES PATENT OFFICE.

FRANK B. WORDEN, OF JAMESTOWN, NEW YORK.

SHEET-METAL HINGE.

1,113,176.

Specification of Letters Patent.

Patented Oct. 6, 1914.

Application filed February 9, 1914. Serial No. 817,674.

To all whom it may concern:

Be it known that I, FRANK B. WORDEN, of Jamestown, in the county of Chautauqua, in the State of New York, have invented 5 new and useful Improvements in Sheet-Metal Hinges, of which the following, taken in connection with the accompanying drawings, is a full, clear, and exact description.

This invention relates to certain improvements in hinges, and more particularly to a sheet metal hinge, applicable to closet seats and seat covers.

The object of the invention is to provide a light and durable hinge formed of sheet metal and which shall at the same time have the rigidity and strength desired.

A further object is to provide a novel means for attaching hinging members to a sheet metal closet seat or cover.

20 In the drawings—Figure 1 is a top plan view of a closet seat showing the hinges applied thereto. Fig. 2 is a side elevation of the same. Fig. 3 is a longitudinal cross section through the portion of the hinge which is shown in Fig. 2 as applied to the seat cover. Fig. 4 is a cross section through the hinging member shown in Fig. 3 on a line corresponding to the line 4—4 in that figure. Fig. 5 is a cross section through the same 25 member on a line corresponding to the line 5—5, Fig. 3. Fig. 6 is a view of the blank from which the hinging member of Fig. 3 is formed. Fig. 7 is a longitudinal cross section through the hinging member adapted to be attached to the seat. Fig. 8 is a cross section of the member shown in Fig. 7 upon a line corresponding to the line 8—8 in that figure and looking in the direction of the arrows. Fig. 9 is a longitudinal cross section 30 of a support for a hinging rod and adapted to be mounted upon a suitable bowl. Fig. 10 is a cross section of a slightly different form of support. Fig. 11 is a cross section of the support shown in Fig. 9 taken upon a line corresponding to the line 11—11 in that figure. Fig. 12 is a cross section of the form of support shown in Fig. 10 taken upon a line corresponding to the line 12—12 in that figure. Fig. 13 is a side elevation 35 of a closet bowl, seat and cover, partly in section, showing a novel means of attaching the hinging members. Fig. 14 is a longitudinal sectional view of a slightly different form of support than that shown in Figs. 9 and 10 in that the washer is formed integral

with and stamped up from the sheet metal. Fig. 15 is a longitudinal sectional view of the hinging member attached to the cover as shown in Fig. 13. Fig. 16 is a longitudinal cross sectional view of the hinging member 60 attached to the seat as shown in Fig. 13.

Referring now, particularly to Figs. 3, 4, 5 and 6, in which is represented a hinging member —1— formed from the sheet metal blank illustrated in Fig. 6, the central portion —2— being return bent to form an eye —3— for the reception of a hinging rod —4— and this eye is preferably provided with a sleeve —5—, as shown in Figs. 7, 9 and 10, adapted to form a reinforced bearing 70 for the hinging rod —4—.

The parts —6— and —7— of the blank are bent into tubular form longitudinally of the blank and the part —6— is so positioned and of such a relative size as to telescope within the part —7—, to reinforce and strengthen the body of the completed member —1—.

The end —8— has its marginal portion struck up, or its central portion depressed, 80 to form a marginal flange —9— forming a seat for the other end —10— of the blank and these end portions —8— and —10— when brought together are provided with registering openings —11— for the reception of screws adapted to attach the member 85 to a seat or cover.

Fig. 7 is a view of the hinging member —11— used in connection with the seat —1— and may be formed in the same manner as the member —1— so that it is of two thicknesses of the sheet metal and reinforced throughout its length, except that it has a bend intermediate its ends adapting it to the particular position in which it is used or it may be, as shown in Figs. 7 and 8, of a single thickness for a considerable portion of its length and in this construction, the return bend portion —13—, forming the eye —3—, has its end bent in tubular form in the same 95 manner as the part —6— forming the member —1—, and this portion —13— telescopes within the body —11— which is likewise of tubular form for a portion of its length as best shown in Fig. 8. In this form of practice, the part —14— having the screw-receiving openings —15— is of a single thickness of material and its marginal portion —16— may be struck up to form a reinforcement, but this is not essential. In many 100 105 110

cases, it is preferable that the part —14— be perfectly flat.

In Figs. 9, 10, 11 and 12, a post —17— is shown for supporting the hinging rod —4— upon which the hinging members —1— and —11— are journaled. Slightly different forms of this post are shown in the respective figures. The post of Fig. 9 is formed practically in the same manner and the resulting product is of the same construction, as the hinging member —1— of Fig. 3, except that its lower portion is circular and threaded for the reception of a washer —18— and a suitable nut —19— for attaching the post to a bowl as shown in Figs. 2 and 13, and the post of Fig. 10 is formed in practically the same manner and the resulting product is of the same construction as the hinging member of Fig. 7 except that in this case, the post is shown with a separate reinforcing rod —20— having its lower end threaded and its upper end telescoping within the sheet metal portion of the post and terminating adjacent the tubular part —21— which telescopes within the body of the post. In each of these post members, the sheet metal is return bent to form an eye —22— and has portions adjacent this eye, telescoping with each other, adapted to reinforce the body of the post. Each post is provided with a washer —18—, formed separate from the post and having a threaded engagement therewith and adapted to engage the upper portion of a bowl to prevent downward movement of the post beyond a predetermined point. It will be readily apparent, however, from Fig. 14 that this post may be entirely formed of a single piece of sheet metal in which the washer —18— is formed integral with and stamped up from the metal.

In Figs. 15 and 16, sheet metal hinging members are shown constructed in the same manner as the hinging members shown in Figs. 1 and 7 and the posts of Figs. 9, 10 and 14. Their shape, however, is slightly different in that they are substantially cylindrical throughout their length and, in Fig. 13, I have shown a novel means for attaching hinging members of this shape to a sheet metal closet seat and cover provided with a suitable reinforcing member. This sheet metal seat, as —23—, and the cover, as —24—, may be constructed in any suitable manner and, as shown, both the seat and cover are provided with a suitable U-shaped reinforcing member —25— with which the threaded portions —26— and —27— of the hinging members —28— and —29— have a threaded relation and, preferably, both the seat —23— and cover —24— are constructed of dished sheet metal plates joined together in such a manner as to have their respective marginal portions overlapped,

and the posts —28— and —29— may likewise have a threaded relation with an inferiorly threaded opening through these plates from which the seat and cover are formed. It will be apparent, however, that this sheet metal seat and cover may be constructed in any of the ways set forth in my co-pending application Serial No. 798,889, filed November 3, 1913, and that these hinging members —28— and —29— may or may not have a threaded relation with the metal forming the body of the seat.

Where joints occur in the hinging members or in the posts or where these members or posts are of two thicknesses of the metal, the joints or parts may be suitably, and either temporarily or permanently, united by soldering, welding or otherwise.

It will now be readily apparent that many changes may be made in the details of construction and in the form of the particular construction herein described without departing from the spirit of this invention as set forth in the appended claims.

What I claim is:

1. A hinging member formed of sheet metal, return bent to form an eye, and having portions adjacent said eye telescoping with each other.

2. A hinging member formed of sheet metal, return bent to form an eye, and having portions adjacent said eye of tubular form and telescoping with each other.

3. A hinging member formed of sheet metal, return bent to form an eye, and having portions adjacent said eye of tubular form and telescoping with each other, and a bushing in said eye.

4. A hinging member formed of sheet metal, return bent to form an eye, and having portions adjacent said eye fitted one within the other.

5. A hinging member formed of sheet metal, return bent to form an eye, and having portions adjacent said eye fitted one within the other and adapted to reinforce the body portion of said member and fixedly determine the size of said eye.

6. A hinging member formed of sheet metal, return bent to form an eye, and having portions adjacent said eye of tubular form and telescoping with each other, and a bushing in said eye abutting against the telescoping portions.

7. A hinging member formed of sheet metal and having an eye at one end and a tubular part intermediate its ends, and means for reinforcing said tubular part.

8. A hinging member formed of sheet metal having an eye at one end and a tubular part leading from the eye, and means for reinforcing said tubular part.

9. A hinging member formed of sheet metal return bent to form an eye and having portions adjacent said eye fitting one

within the other, one of the end portions dished and the other end portion seated in said dished portion.

10. A hinging member formed of sheet metal return bent to form an eye and having portions adjacent said eye fitting one within the other, one of the end portions dished and the other end portion seated in

and conforming in shape to said dished portion.

In witness whereof I have hereunto set my hand this 30th day of January, 1914.

FRANK B. WORDEN.
